UNITED STATES PATENT OFFICE.

HOWARD J. WHITE, OF SAN FRANCISCO, CALIFORNIA.

BOX FOR ELECTRIC CONDUITS.

1,078,181.

Specification of Letters Patent. Patented Nov. 11, 1913.

Application filed October 6, 1910. Serial No. 585,678.

To all whom it may concern:

Be it known that I, HOWARD J. WHITE, of San Francisco, California, have invented certain new and useful Improvements in 5 Boxes for Electric Conduits, whereof the following is a specification.

This invention relates to terminal boxes for electric conduit connections, such, for example, as are placed in the ceilings of 10 rooms for connection of the electroliers.

The object of the invention is to produce a cheap and simple box, and one which is adaptable to a multiplicity of positions, and thus avoid the necessity of a multiplicity of 15 forms.

In carrying out the invention I make a dual box of two shells, one of which is perforate, and the other imperforate. The perforate shell I make of heavier material 20 than the other, which I make of thin material, so that it may be reamed out in register with any of the perforations of the thicker shell, and thus provide an opening for the conduit with which it is desired to 25 connect.

Other features of the invention, as also the structural details, will appear in the accompanying drawings, and the description which follows hereinafter.

30 In the drawings:—Figure 1 is a sectional elevation, taken centrally of a box and shows a perforate inner shell, an imperforate outer shell and a cover, with the method of fastening the cover. Fig. 2 is a similar view, 35 but shows also two conduits applied to the box and the method of securing them, the outer shell being reamed out at two points for their ends. Figs. 3 and 4 are, respectively, cross-sections taken at the lines, 40 3—3 and 4—4, of Fig. 1.

In the figures:—1 represents a cup shaped shell perforated at suitable points with holes 2 of a size to receive the ends of conduits, and with such other holes, as 3, as may 45 be desirable for fastening devices.

4 represents an imperforate shell fitting over the outside of shell 1, and made of thinner material. The two shells may be connected in any suitable manner, such as dipping in a galvanizing or tinning bath, or 50 otherwise.

5 are center punch marks in shell 4, registering with the various perforations of shell 1.

55 6 represents a cover or closure for the

mouth of the two shells, which may be perforated, as at 7, for electrolier connections, or other purpose.

The manner of securing the cover 6 to the shells is as follows, viz:—8, 8, are two 60 cleats, which may be made of strap iron, or brass, or other material. The ends of these cleats are turned at right angles and engaged in holes 3 in the sides of shell 1. The body of each cleat extends down along 65 the side of the shell, and its lower end is turned inward across the lower edge of the shell. In this lower end of the cleat is tapped a hole 9, which is engaged by a screw 10 passing through the cover 6. The outer, 70 imperforate, shell 4 is formed with a recess 11 to bridge over and accommodate the cleat at each side. Thus the cleats are inclosed between the two shells and securely held.

12 are fastenings, as nails, by which the 75 box is secured to a beam or other member 13.

Referring now more particularly to Fig. 2, 14 are conduits, containing the electric wires 15, for connection to whatever fixture is to be applied to the box. It having been 80 decided at what point the conduit is to enter the box, the outer shell is perforated at that point by inserting the end of a reamer in the appropriate punch mark 5 and reaming out a hole in register with the corresponding 85 hole 2 of the inner shell. The end of the conduit, which is threaded and provided with a nut 16, is inserted into the perforation thus provided, and a cap 17 screwed upon its end thus clamping the box between itself and the nut 16. The cap 17 is 90 perforated for the passage of the wires 15, and the hole is rounded to prevent mutilation of the wires.

Having thus described my invention, and 95 believing that I have made a new and valuable improvement in the art to which it pertains, I claim:—

1. In a conduit box, in combination, a perforate shell and an imperforate shell, the 100 imperforate shell being outside of and inclosing the perforate shell.

2. In a conduit box, in combination, a perforate shell and an imperforate shell, the imperforate surrounding the perforate 105 shell and provided with punch marks opposite its perforations.

3. In a conduit box, in combination an inner and outer shell, a cover for said shells, means to secure said cover to said shells con- 110

sisting of metallic strips located between said shells, the ends of which are turned inwardly, said inner shell provided with holes in the side thereof engaging one end of said strips and means on the cover engaging the opposite ends.

In testimony that I claim the foregoing

I have hereto set my hand this 24th day of September, 1910, in the presence of witnesses.

HOWARD J. WHITE.
